UNITED STATES PATENT OFFICE.

WILLIAM HITT BOGGS, OF COVINGTON, OHIO.

DESIGN FOR A HAT-TREE.

SPECIFICATION forming part of Design No. 35,223, dated October 22, 1901.

Application filed September 23, 1901. Serial No. 78,802. Term of patent 14 years.

To all whom it may concern:

Be it known that I, WILLIAM HITT BOGGS, a citizen of the United States, residing at Covington, in the county of Miami and State of Ohio, have invented and produced a new and original Design for Hat-Trees; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to an original design for hat-trees; and it consists in the shape or form of the same, being novel in its contour or outlines, as is clearly shown and fully illustrated in the annexed drawings, in which like letters of reference refer to the same parts wherever they occur throughout both views, and in which—

Figure 1 is a perspective view of a hat-tree embodying my new and original design; and Fig. 2 is a plan view of the same, partially in section, taken on the line $\alpha\alpha$ of Fig. 1.

As shown in the drawings, the essential or distinctive features of my new and original

design for hat-trees consist of the feet *a*, above which is the base *b*, and the standard *c* or tree proper, *c*, said tree being formed at its lower end into supports or legs *d* and being further formed with the slots *e*, from which project the arms or branches *f*. Said standard or tree *c* is rectangular in form when taken in cross-section, as clearly shown in Fig. 2. The arms or branches are designed more especially for supporting hats and over-coats, although various other articles of apparel may be placed upon them.

The whole arrangement and relation of the parts above described present an attractive, catchy, and novel appearance and gives an effect to the eye of the observer that is at once both pleasing and distinctive.

Having now described my invention, what I claim as new and original is—

The design for a hat-tree substantially as herein shown and described.

In testimony whereof I have affixed my signature in presence of two witnesses.

WILLIAM HITT BOGGS.
